UNITED STATES PATENT OFFICE

AUGUST C. SPAHN, OF EVANSVILLE, INDIANA, ASSIGNOR TO BERNARDIN BOTTLE CAP COMPANY, OF EVANSVILLE, INDIANA, A CORPORATION OF INDIANA

CLOSURE CAP

Application filed February 10, 1928. Serial No. 253,307.

The invention relates to closure caps of the type which are adapted to grip frictionally the upper or top portion of a rigid container having a substantially straight cylindrical side wall.

The object of the invention is to provide an improved cap of this type which will be securely held by friction against the side wall of the container and will still be effective after removal and upon replacement to grip frictionally the container.

The invention consists in the several novel features hereinafter set forth and more particularly defined by the claims at the conclusion hereof.

In the drawing: Fig. 1 is a vertical section of a cap embodying the invention. Fig. 2 is a side elevation. Fig. 3 is a plan, a portion being broken away.

The invention is exemplified in a cap which is formed of slightly resilient sheet metal, and comprises a top wall 4 and a depending integral annular skirt 5. The skirt is formed with a series of annular corrugations 6 having inner and outer reversely curved crowns. There are sufficient of these corrugations to form a plurality (preferably three) of inner crowns to form substantially continuous annular frictional container-gripping surfaces 7 which are spaced apart vertically, so that the straight wall portion 8^a of a container 8 will be frictionally gripped on lines or zones spaced apart vertically. The lower margin of the skirt 35 extends outwardly from the lowermost gripping surface 7, as at 9, and its lower edge is doubled upon itself, as at 10, to form a reinforced or stiffened lower edge. A disk 11 of paraffin paper or other suitable material is interposed between the upper margin of the rim of the container and the top 4 of the cap, as well understood in the art.

The gripping surfaces 7 are vertically aligned, so that normally they all frictionally grip the container with substantially the same force. By providing a plurality of these gripping surfaces, the gripping force will be cumulated according to the number

of such surfaces, so that the cap will be securely held on the container.

In practice, when it is desired to remove the cap, it is customary to strike the lower edge 9 of the cap to produce a peening effect 55 on the metal forming the gripping surfaces which will cause such surfaces to relax sufficiently to permit the cap to be removed from the container. This striking of the margin has a more direct peening effect 60 upon the metal forming the lowermost gripping surface and less of such effect on the surfaces located more remotely from the lower edge. As a result the resilience of the uppermost gripping surface will remain 65 effective to grip frictionally the container after the cap has been removed and is replaced. If the container happens to be oversize, the cap can be removed by tapping the outer crowns of the upper corrugations 70 as well as the lower edge. The corrugations are formed on comparatively short radii, so that the desired number of gripping surfaces may be provided without a skirt 75 of unwieldy height.

The invention exemplifies a closure cap of the frictionally gripping type for straight cylindrical containers in which the frictional gripping of a plurality of annular surfaces against the straight side of the container is 80 cumulated to retain securely the cap on the container; also a cap of this type which may be caused to release its grip upon the container by tapping the lower portion thereof, and leaving the metal forming the upper 85 gripping surface substantially effective for gripping, so that the cap may be replaced with sufficient gripping force to effectively retain it on the container.

The invention is not to be understood as 90 restricted to the details set forth, since these may be modified within the scope of the appended claims, without departing from the spirit and scope of the invention.

Having thus described the invention, what 95 I claim as new and desire to secure by Letters Patent, is:

1. A closure cap for a container having a substantially straight cylindrical side-wall adjacent to its upper end, said cap com. 100

prising a top and a depending integral skirt of resilient metal, the skirt having annular corrugations with inner crowns rounded and forming a plurality of substantially continuous annular frictional container-gripping surfaces which are spaced apart vertically, the skirt extending outwardly from the lowermost gripping surface so its lower edge will be spaced from the container wall 10 and form a portion which may be tapped in order to effect a peening of the contiguous metal for cap removal purposes, the annular corrugations of the skirt being of such number and character that the inner crown 15 parts remote from the outwardly extending part of the skirt are subjected, during tapping, to a less peening effect than the lower crown parts and consequently retain sufficient resiliency to grip frictionally and securely 20 the container upon replacement of the cap on the container.

2. A closure cap for a container having a substantially straight cylindrical side-wall adjacent to its upper end, said cap comprising 25 a top and a depending integral skirt of resilient metal, the skirt having annular corrugations with inner crowns rounded and forming a plurality of substantially continuous annular friction container-gripping 30 surfaces which are spaced apart vertically, the skirt having its lower margin stiffened and flared outwardly from the lowest gripping surface to form a portion that is spaced from the container and is adapted 35 to be tapped in order to effect a peening of the contiguous metal for cap removal purposes, the annular corrugations of the skirt being of such number and character that the inner crown parts remote from the outwardly flared lower margin of the skirt are 40 subjected, during tapping, to a less peening effect than the lower crown parts and consequently retain sufficient resiliency to grip frictionally and securely the container upon 45 replacement of the cap on the container.

3. A closure cap for a container having a substantially straight cylindrical side wall adjacent to its upper end, said cap comprising 50 a top and a depending integral skirt of resilient metal, the skirt having annular corrugations the outer and inner crowns of which are rounded and of similar conformation, the inner crowns forming three substantially continuous annular frictional container-gripping surfaces which are spaced apart vertically and are adapted to grip directly and frictionally the side wall of the container, the skirt extending outwardly from the lowermost gripping surface so its 55 lower edge will be spaced from the outer periphery of the container side wall.

Signed at Evansville, Indiana, this 30 day of January, 1928.

AUGUST C. SPAHN.
